UNITED STATES PATENT OFFICE.

GEORGE EDWARD WORTH, OF ROCHESTER, NEW YORK, ASSIGNOR TO JESSE H. WEBB
AND JOHN GELL, BOTH OF ROCHESTER, NEW YORK.

DESIGN FOR A CHILD'S VEHICLE.

54,161.

Specification for Design.

Patented Nov. 4, 1919.

Application filed May 24, 1919. Serial No. 299,672. Term of patent 14 years.

To all whom it may concern:

Be it known that I, GEORGE EDWARD WORTH, citizen of the United States, residing at Rochester, in the county of Monroe and State of New York, have invented a new, original, and ornamental Design for a Child's Vehicle, of which the following is a specification.

Figure 1 is a top plan view of the vehicle illustrating my new design.

Fig. 2 is a side elevation of the vehicle shown in Fig. 1.

Fig. 3 is an end elevation of the vehicle shown in Fig. 1, and viewed from the right hand end of the figure.

I claim:

The ornamental design for a child's vehicle as shown.

In testimony whereof I affix my signature.

GEORGE EDWARD WORTH.
